E. J. LANG

CUT-OUT PANEL

Filed Oct. 20, 1924

Fig. 1.

Fig. 2.

INVENTOR:
Edward J. Lang,

By Wm. F. Freudenreich. Attest

UNITED STATES PATENT OFFICE.

EDWARD J. LANG, OF CICERO, ILLINOIS.

CUTOUT PANEL.

Application filed October 20, 1924. Serial No. 744,691.

To all whom it may concern:

Be it known that I, EDWARD J. LANG, a citizen of the United States, residing in Cicero, county of Cook, State of Illinois, 5 have invented a certain new and useful Improvement in Cutout Panels, and declare the following to be a full, clear, and exact description of the same, such as will enable others skilled in the art to which it pertains 10 to make and use the same, reference being had to the accompanying drawings, which form a part of this specification.

The present invention relates to panel boards which are the centers from which 15 electrical energy is distributed to light and power circuits, and has for its object to produce a construction that shall be simple, novel and compact, while at the same time permitting the use of two independent terminals 20 for each fuse receptacle.

The various features of novelty whereby my invention is characterized will herein-after be pointed out with particularity in the claims; but, for a full understanding 25 of my invention and of its objects and advantages, reference may be had to the following detailed description taken in connection with the accompanying drawings, wherein:

30 Figure 1 is a plan view of a panel arranged in accordance with a preferred form of my invention and Fig. 2 is a section on an enlarged scale taken approximately on the line crossed by the arrow in Fig. 1 35 and having associated therewith the indicating character 2.

Referring to the drawing, 1 and 2 represent two main bus bars either of which may be the positive and the other the negative; and 3 is a neutral bus bar which, in the arrangement shown, is in the form of a single element lying between the other two bars. In the arrangement shown, the parts are mounted on a suitable base 4 of 45 insulating material, the bar 3 lying flat on the base and extending along the longitudinal center of the latter, while the bars 1 and 2 are bent upwardly adjacent to the ends that constitute the main terminals, so 50 that the major portions of these two bars lie at a considerable distance above and parallel with the base. Connected with the bar 3 are cross pieces 5 extending at right angles thereto and each having at each end 55 a screw 6 or other means for attaching a wire. In other words, regardless of whether

the neutral bar be a single element or not, the arrangement is such that the neutral element is provided with two rows of terminals arranged one row near one edge of 60 the base and the other row near the opposite edge.

The bus bars 1 and 2 pass lengthwise through blocks of insulating material in 65 which are mounted fuse receptacles, each receptacle being electrically connected with the adjacent main bus bar and having a terminal lying above one of the terminals 6. Therefore two feed wires in a circuit 70 in which any fuse receptacle is located may be connected to two terminals lying in approximately the same transverse plane, but at different elevations, instead of two terminals lying side by side, which latter arrangement causes an increase in the length 75 of the panel.

In the arrangement shown, there are twelve fuse receptacles 7, six above each of the two bus bars 1 and 2. Furthermore, 80 each block of insulating material through which one of the bus bars passes, is shown as made up of three sections 8, arranged end to end, there being two receptacles in each section. However, this particular arrangement is not of importance except that 85 it affords a means for providing individual units that may be assembled conveniently to form a panel of any desired length and containing any desired number of sockets or fuse receptacles. In the arrangement 90 shown, each insulating block section is provided with a lateral projection 9, and there is a screw 10 passing downwardly through this projection into the base, for securing the insulating member to the base. 95

The fuse receptacles are shown as taking a conventional form, each consisting of a shell fitting in a socket 11 in the insulating block and having a central terminal 12 in the form of a screw that passes through the bottom of the same and is engaged with the underlying bus bar. The shell member of the receptacle has attached thereto a metal bar 13 that extends laterally therefrom and lies on top of a low portion 14 of the insulating block arranged on the outer side of the block. Each of the short bars 13 is provided with a screw 15 or other means for attaching a wire. The parts are so proportioned that each of the terminals 6 connected with the neutral bus bar lies just beyond the outer edge of the corresponding 105 110

insulating block, while each of the terminals 15 lies in about the same transverse plane as one of the terminals 6. It will thus be seen that two feed wires forming part of a circuit in which one of the fuses is to be placed, may be connected to a terminal 15 and a terminal 6 lying one above the other but spaced apart far enough to prevent interference with each other. There is always 10 available room in the vertical direction and therefore the panel as a whole need not be thickened in order to permit the terminals to be displaced vertically of each other; whereas it would be necessary to lengthen the 15 panel if the terminals were placed side by side.

There are several features to which reference has not yet been specifically made, but which are of considerable value. One of 20 these features has to do with the provision of means for permitting the same structure to be used conveniently with switches in addition to the fuse receptacles. Therefore, I have cut through the inner side of each 25 insulating block, below each receptacle, a slot 16 in the plane of the corresponding main bus bar; whereby switches may be placed beside the insulating blocks and be connected to the bus bars through the slots.

30 Another feature relates to the upper feed-wire terminals. It will be seen that the bars 13 are connected to the shells of the fuse receptacles by screws 17, one screw for each bar. These screws pass down through the 35 inner ends of the bars into screw-threaded sleeves 18 molded directly into the blocks. In the same way, the terminal screws 15 pass through the outer ends of the bars 13 and into screw-threaded sleeves 19 molded 40 into the outer portions of the blocks which form the shoulders 14.

While I have illustrated and described with particularity only a single preferred form of my invention, I do not desire to be 45 limited to the exact structural details thus illustrated and described; but intend to cover all forms and arrangements which come within the definitions of my invention constituting the appended claims.

50 I claim:

1. A cutout panel comprising two main bus bars, fuse receptacles distributed along each bar and electrically connected therewith, a terminal for a feed wire associated 55 with each receptacle, a second terminal arranged directly below and spaced apart from each of the aforesaid terminals, and

means connecting said second terminals to a neutral conductor.

2. A cutout panel comprising two main 60 bus bars, fuse receptacles distributed along each bar and electrically connected therewith, two feed-wire terminals for each receptacle arranged one directly above the other, one terminal of each pair being connected to the corresponding receptacle and the other being connected to a conductor common to all of the corresponding terminals.

3. A cutout panel comprising two blocks 70 of insulating material, a bus bar passing through each of said blocks, a plurality of fuse receptacles in each block, each receptacle being electrically connected with the corresponding bar, two feed-wire terminals 75 arranged beside each receptacle and arranged one directly above the other, one terminal of each pair being connected to the corresponding receptacles and the other terminals being connected to the corresponding terminals of the other pairs.

4. A cutout panel comprising a base, two separated blocks of insulating material on said base, a bus bar passing through each of said blocks, a plurality of fuse receptacles 85 in each block electrically connected to the corresponding bar, a terminal for a feed wire associated with each receptacle and located on the outer side of the corresponding block at a considerable distance above said 90 base, a neutral bar extending through the space between the blocks, and a series of terminals corresponding in number to the aforesaid terminals electrically connected with said neutral bar and each located on 95 the base below one of the first-mentioned terminals.

5. In combination, a base, a bar of conducting material overlying said base, a series of cross arms connected with the aforesaid 100 bar, a terminal for a feed wire at each end of each of said arms, blocks of insulating material overlying said arms, fuse receptacles in said blocks, two bus bars extending through said blocks and each electrically 105 connected with the corresponding fuse receptacles, and terminals for feed wires mounted on said blocks above the aforesaid terminals and electrically connected to said receptacles.

In testimony whereof, I sign this specification.

EDWARD J. LANG.
